HAIR CURLER

Rudolf Krasberg, Chicago, Ill., assignor to Chain
Store Products Corporation, Chicago, Ill., a
corporation of Delaware

Application March 16, 1936, Serial No. 69,028

4 Claims. (Cl. 132—41)

This invention relates to hair curlers, and more particularly to hair curling devices of the type including a pair of pivotally connected cooperating members for gripping a strand of hair, and about which the hair is wound to form a curl, and a clamping bail pivotally connected to the gripping members and adapted to be swung into cooperative relation to said gripping members for maintaining the hair in curled form thereon.

One of the objects of this invention is to provide means adapted for engaging both hair gripping members for releasably locking them in operative gripping relation when the hair is wound thereon.

Another object is to provide a novel form of clamping bail, adapted when disposed in operative position, for releasably locking the gripping members in operative relation to maintain and insure a positive and firm grip on the hair preparatory to winding thereon to form a curl, and also during the time said hair remains wound thereon.

A further object resides in the provision of an improved, pivotally mounted clamping bail of generally U-shape form, and which is so constructed that when it is swung into operative relation to the gripping members the side portions of said clamping bail engage both of the gripping members for releasably locking them together in operative relation, with the closed end portion of the bail disposed in spaced apart relation to the adjacent end portions of the gripping members permitting use of the maximum curling length of the gripping members.

A still further object of this invention is to provide an improved hair curler of the above mentioned type which is of simple construction and which may be economically manufactured.

Other objects and advantages of this invention will appear in the following description, taken in connection with the accompanying drawing, in which:—

Fig. 1 is a side view of a curler device embodying the present invention, shown in closed position.

Fig. 2 is a similar view, with the clamping bail disposed in open position, and the parts being indicated in dotted outline at open position for receiving a strand of hair.

Fig. 3 is a top view of the device shown in closed position.

Figs. 4 and 5 are enlarged transverse sections, taken as indicated at lines 4—4 and 5—5, respectively, on Fig. 1.

The structure selected for illustrating the pres-

ent invention includes a pair of cooperatively formed gripping members, 10 and 11, the former being of slightly tapered tubular form, while the latter is of convexo-concave cross section shaped to embrace the upper portion of the tubular member 10, when said members are disposed in closed position. The operative portions of said members may be of coextensive length, but preferably, as shown in the drawing, the upper gripping member 11 terminates a short distance from the end of the tubular member 10. Said gripping members, 10 and 11, are preferably formed of light weight sheet metal, such as aluminum, or other suitable material, and are provided with a plurality of perforations or apertures, 12 and 13, respectively. The tubular member 10 is formed with a pair of spaced apart upstanding apertured ears, 14, and the member 11, is formed with a pair of spaced apart depending apertured ears, 15, disposed in straddling relation to the ears 14 of the tubular member, and both pair of said ears are pivotally mounted on a transverse pivot pin 16 which also secures the members against separation. Said gripping members 10 and 11 are provided with finger grip portions 18 and 19, respectively, extending rearwardly of the pivot connection, and which may be pressed toward each other for swinging the gripping members about their pivot connection for causing separation thereof, as indicated in dotted outline in Fig. 2, to permit insertion of a strand of hair therein, preparatory to winding the hair therearound to form a curl.

After the hair is wound around the gripping members 10, and 11, the curled hair is secured in shape on said gripping members by a resilient clamping bail 21, of generally U-shape formation. The ends of the clamping bail are pivotally connected at 22 and 23 to the finger grip portions 18 and 19 of the respective gripping members 10 and 11, at an axis extending transversely to the pivot axis of said gripping members, as may be seen in the drawing, which permits said bail to be swung to and from operative position. The closed end portion of the bail is formed and dimensioned so that when the bail is in operative position said closed end portion is disposed in spaced relation to the gripping members, as seen in Fig. 1, permitting use of the maximum curling length of said gripping members. Because of the resilient character of the bail and its connection to the finger grip portions 18 and 19, it normally tends to separate the finger grip portions and thus yieldingly urges and

55 50 55

maintains the gripping members 10 and 11 in operative relation.

The legs of the clamping bail are each formed with an offset portion, indicated at 25 and 26, adapted when the bail is swung to operative position, for registering and interlocking with cooperatively formed seats provided in the gripping members 10 and 11, forwardly of their pivot connection, as may be seen in the drawing, for 5 releasably locking the gripping members in operative relation to each other. Said seats are herein shown in the form of slots, 27 and 28, and it will be manifest that said seats may be formed as depressions or embossments, to provide 10 interlocking engagement with the offset portions of the bail when it is disposed in operative position. When the clamping bail is disposed in operative position, with the hair curled around the gripping members, the hair cannot accidentally 15 become released from the gripping members because they are positively locked together.

The curling device may be permitted to remain on the strand of hair for a sufficient period of 20 time to insure that the hair will remain in curled form when the device is removed and as many of these devices as desired may be employed at the same time, and may be worn with comfort while sleeping.

30 Although I have herein shown and described a preferred embodiment of my invention, manifestly the form and arrangement of parts may be varied and modified without departing from the spirit and scope of my invention. I do not, 35 therefore, wish to be understood as limiting my invention to the specific form herein shown and described, except as so limited in the appended claims.

I claim as my invention:

40 1. A hair curler comprising a pair of pivotally connected gripping members between which the hair may be engaged and about which the hair may be wound, both of said members having finger grip portions at their rear ends, adjacent 45 said pivot connection, and a clamping bail having its ends pivotally connected to the respective finger grip portions of said members, said clamping bail being formed for engaging both of said members adjacent their pivot connections, when

it is disposed in operative position, for releasably locking said members together.

2. A hair curler comprising a pair of pivotally connected gripping members between which the hair may be engaged and about which the hair may be wound, both of said members having finger grip portions at their rear ends, adjacent 5 said pivot connection, and a resilient clamping bail having its ends pivotally connected to the respective finger grip portions of said members 10 for normally urging said members toward each other, said clamping bail being formed for engaging both of said gripping members adjacent their pivot connections, when it is disposed in operative position, for releasably locking said 15 gripping members together.

3. A hair curler comprising a pair of pivotally connected gripping members between which the hair may be engaged and about which the hair may be wound, both of said members having 20 finger grip portions at their rear ends, adjacent said pivot connection, and a clamping bail having its ends pivotally connected to the respective finger grip portions of said members for swinging to and from operative position, said clamping bail being formed with offset portions adapted, when it is disposed in operative position, for 25 engaging seats formed in both of said gripping members adjacent their pivot connections, for releasably locking them in gripping relation. 30

4. A hair curler comprising a pair of pivotally connected gripping members between which the hair may be engaged and about which the hair may be wound, both of said members having finger grip portions at their rear ends, adjacent 35 said pivot connection, and a clamping bail of generally U-shape formation having its ends pivotally connected to the respective finger grip portions of said members for swinging to and from operative position, said bail being dimensioned and formed so that, when disposed in operative position, its intermediate portion is disposed in spaced relation to the ends of said gripping member, while side portions of said clamping bail engage both of said gripping members, adjacent their pivot connections, for 40 releasably locking them in gripping relation.

RUDOLF KRASBERG.
